UNITED STATES PATENT OFFICE.

GIUSEPPE CARMELO LARAIA, OF NEW YORK, N. Y.

HEADREST FOR BARBER OR LIKE CHAIRS.

1,394,913.

Specification of Letters Patent.

Patented Oct. 25, 1921.

Application filed June 28, 1918. Serial No. 242,406.

To all whom it may concern:

Be it known that I, GIUSEPPE CARMELO LARAIA, a citizen of the United States of America, residing in the borough of Manhattan, city, county, and State of New York, have invented certain new and useful Improvements in Headrests for Barber or like Chairs, of which the following is a specification.

10 This invention relates to improvements in head rests for barber or like chairs and aims to provide improvements therein.

The invention provides a head rest of the type in which the upper surface is covered 15 with a sheet of paper, wherein improved means are provided for holding the paper smooth and taut over the head rest and for shielding the roll of paper, from which the paper is supplied, when the head rest is 20 turned back in its out-of-use position.

The invention further provides a head rest which is of simple and economical construction, and which functions simply and reliably.

25 An embodiment of the invention is illustrated in the accompanying drawings, wherein—

Figure 1 is a rear elevation of the head rest, shown applied to a chair, looking in 30 the direction of the arrow I, Fig. 2.

Fig. 2 is a vertical section on the line 2—2, Fig. 1;

Fig. 3 is a rear view of the head rest.

35 Fig. 4 is a horizontal section on the line 5—5, Fig. 2;

Fig. 5 is a perspective view of a detail part of the mechanism.

Referring to said drawings, A designates the back of a chair, B the head rest, and C 40 a post or rack bar upon which the head rest is preferably connected in a manner to permit to be swung out of the way when its use is not desired.

The head rest B is conveniently composed 45 of a frame comprising a casting 1, side plates 2 secured to the casting, and a pad 3 which may be conveniently supported by coiled springs 4 attached at their ends to the side plates 2.

50 6 designates a roll of paper, and this roll is supported in the head rest by a rod 7 passing through the bobbin or core of the paper roll. The rod 7 may be conveniently supported at one end in a recess 8 in one 55 of the side plates 2, and at its other end in a recessed cap screw 9 having a threaded en-

gagement with the other side plate 2, as indicated at 11.

13 designates a shield and friction member, having a concave part adapted to bear 60 against the underside of the roll when the roll is in the position shown in Fig. 2, that is, the in-use position of the head rest. This shield and friction member is carried by a rod 14 which is pivoted at its ends in a 65 part of the frame, as the casting 1, and is pressed into contact with the roll by a coiled spring 15 having one end attached to said shield, and its other end held by a nut 16 upon the screw 17 which may be used for 70 securing the side plate to the casting 1, at each side. The shield 13 may be provided with a projection 18 adapted to strike against the cap screw 9 when the roll of paper 6 is removed, thus limiting the move- 75 ment of the shield 13.

The paper web unwinding from the roll 6 passes over the pad 3, and passes between the jaws of a clamp 20 opposite the roll 6. The clamp 20 preferably comprises a plate 80 21 secured by ears 22 to a rod 23 fixed at its ends in the side plates. The lower end of the plate 22 is curled around a rod 24 also fixed at its ends in the side plates 2. This plate 21 also serves as a guide when the end 85 of the paper web is threaded through the jaws of the clamp.

26 designates the complementary jaw member, and comprises a plate 27 having ears 28, and having its upper jaw 29 curled and constituting a portion which presses the web 90 of paper against the other jaw member.

The ears 28 are provided with elongated slots 30 and 31; the rod 24 passing through the slot 30, and a rod 33 passing through 95 the slot 31.

The jaw member 26 (particularly the part 29 thereof) is pressed against the plate 21 by means of a plate 35. The plate 35 has ears 36 through which the rod 23 passes, 100 and on which rod the plate 35 may turn. A spring 37 having one end connected to the plate 35, and its other end passing through a hole 38 in the ear 22 (which is fixed) presses the plate 35 in a direction to press 105 the plate 27, and hence press the jaw member and the part 29 down upon the opposite jaw member or plate 21.

The lower edge of the plate 27 is preferably sharpened, as indicated at 39, to provide an edge against which the paper may 110 be torn.

Means are preferably provided for open-plate having means adapted to strike against the jaws and displacing the plate 27 in a stop to limit the inward movement when a manner to permit the leading edge of the paper (which is behind the plate 27) being

- 5 conveniently grasped. These means preferably comprise a rod 40 pivotally mounted in the side plates 2, as indicated at 41, 42, provided with a thumb piece 43, and has fixed thereon arms 45, 45 which are adapted 10 to come into contact with flanges 46, 46 formed upon the ears 28 of the clamp part 26.

Operation: Paper is unwound from the roll 6, passed over the pad 3, and threaded between the parts 24 and 29 of the clamping parts 21 and 26. To facilitate the threading of the paper between the parts 24, 29, the thumb piece 43 is turned, causing the arms 45 carried by the shaft 40 to press upon the flanges 46 and press the part 26 forwardly 20 and upwardly (by reason of the slotted portions 30, 31 moving over the pins 24, 33) and plate 35 yields against the resistance of its spring 37. The leading edge α of the paper then projects in plain view and accessibility, and may be grasped to unwind a paper from the roll 6, and thus present a fresh portion over the pad 3.

When sufficient of the paper has been unrolled, the thumb-piece 43 may be released, 30 permitting the plate 35 to press the clamping part 26 downward and inward, bringing the part 29 against the part 21, and thus firmly clamping the paper.

The used portion of paper may be conveniently detached by tearing it against the cutting edge 39.

The paper is held taut and smooth over the head rest by reason of the friction of the part 13 upon the roll 6, and by reason of 40 the firm grip upon its other end by the parts of the clamp 20.

The frame, preferably the casting 1 thereof, is provided with a plate 50 which projects between two ears 51, 52 upon the end 45 of the post or rack bar C and 53 indicates a pin pivotally connecting the plate 50 to the post C.

When the head rest is inverted, the shield 13 acts to protect the roll of paper 6. 50 The means for raising and lowering the head rest and the means for connecting the head rest proper to its post or rack-bar are set forth and claimed in a divisional application filed July 24, 1920, serially numbered 55 398,713.

The inventive ideas herein set forth may be otherwise embodied than as herein specifically illustrated and described.

What is claimed is:

60 1. A barber or like chair head rest, comprising a paper roll, and a paper clamp, and a plate bearing upon said roll and forming a friction clamp and shield for completely covering one side of said paper roll, and 65 means for removably holding said roll, said

the roll is removed.

2. A barber or like chair headrest, comprising a paper roll and a paper clamp, said clamp comprising a fixed part, a movable member, said movable member comprising a plate having slotted ears permitting sliding and rotating movement thereof, said fixed part comprising a rod running across the head rest and passing through the slots in said ears, and means pressing said movable member into clamping relation with said fixed part.

3. A barber or like chair headrest, comprising a paper roll and a paper clamp, said clamp comprising a fixed part, a movable member, said fixed part comprising a rod running across the headrest and a plate mounted upon said rod, said movable member comprising a plate having slotted ears permitting sliding and rotating movement thereof and means pressing said movable member in clamping relation with said fixed part.

4. A barber or like chair head rest, comprising a paper roll and a paper clamp, said clamp comprising a fixed part, a movable part, said fixed part comprising two rods running across the head rest, and a plate having ears passed through by one of said rods and having an edge turned around the other of said rods.

5. A barber or like chair head rest, comprising a paper roll and a paper clamp, said clamp comprising a fixed part, a movable part, said movable part comprising a plate having a curled edge forming the active clamping portion and slotted ears permitting rotating and sliding movement thereof.

6. A barber or like chair head rest, comprising a paper roll and a paper clamp, said clamp comprising a fixed part, a movable part, said movable part comprising a plate having a curled edge forming the active 110 clamping portion, slotted ears, and a rod fixed to the head rest passing through said slots in said ears and around which said movable part may turn and on which it may slide, whereby, when moved to an 115 clamping position, said movable part may move up and away from the lower side of the paper.

7. A barber or like chair head rest, comprising a paper roll and a paper clamp, said 120 clamp comprising a fixed part, a movable part, said movable part comprising a plate having a curled part forming the active clamping portion, a cutting edge below said clamp, and a loose connection with the head 125 rest permitting upward and outward movement thereof adapted to expose the edge of the paper adjacent said clamp, for convenience in grasping.

8. A barber or like chair head rest, com-

- prising a paper roll and a paper clamp, said clamp comprising a fixed part, a movable part, said movable part comprising a plate having a curled edge forming the active 5 clamping portion, a cutting edge below said curled edge and slotted ears permitting rotating and sliding movement thereof.
9. A barber or like chair head rest, comprising a paper roll and a paper clamp, said 10 clamp comprising a fixed part, a movable member, said movable member comprising a plate having slotted ears permitting a rotating and sliding movement thereof, means for moving said movable member, said means 15 comprising a rotatable rod having an arm and finger-piece thereon.
10. A barber or like chair head rest, comprising a paper roll and a paper clamp, said clamp comprising a fixed part, a movable 20 part, said movable part comprising a plate having slotted ears permitting upward and outward movement of said movable part.
11. A barber or like chair head rest, comprising a paper roll and a paper clamp, said 25 clamp comprising a fixed part, a movable part, said movable part comprising a plate having slotted ears permitting upward and outward movement of said movable part, and a rod having a finger-piece projecting 30 at one side of the head rest and having means thereon for moving said movable part.
12. A barber or like chair headrest, comprising a paper roll and a paper clamp, said 35 clamp comprising a fixed part, a movable part, a rod running across said headrest, said fixed part being attached to said rod, said movable part having a loose connection with said rod, and a spring pressed part pressing 40 said movable part in clamping relation with said fixed part.
13. A barber or like chair head rest, comprising a paper roll and a paper clamp, said clamp comprising a fixed part, a movable 45 part, a spring-pressed plate pressing said movable part into clamping relation with said fixed part, a rod running across said head rest, said fixed part being attached to said rod, said spring-pressed plate being 50 pivoted on said rod, and a second rod to which said fixed part is also connected, said movable clamp-part having a loose connection with said second rod.
14. A barber or like chair head rest, comprising a paper roll and a paper clamp, three rods running from side to side of said 55 head rest, said clamp comprising a fixed plate attached to two of said rods, a movable plate having a slotted connection with two of said rods and movable outward and upward, and a spring-pressed plate pivoted upon one of said rods pressing said movable plate against said fixed plate, said movable plate, when moved upward exposing, 60 for convenient grasping, the edge of the paper released from the clamp by the outward movement of said movable plate.
15. A barber or like chair head rest, comprising a paper roll and a paper clamp, three rods running from side to side of said head 70 rest, said clamp comprising a fixed plate attached to two of said rods, a movable plate having a slotted connection with two of said rods and movable outward and upward, and a spring-pressed plate pivoted upon one of said rods, pressing said movable plate against said fixed plate, said movable plate, when moved, exposing, for convenient grasping, the edge of the paper released from the clamp by the movement of said movable 75 plate, and means for moving said movable plate comprising a rod having a finger-piece and an arm thereon adapted to contact with said movable plate.
16. A barber or like chair head rest, comprising a paper roll and a paper clamp, said 80 clamp comprising a fixed part and a movable part, said movable part comprising a plate having slotted ears permitting a rotating and sliding movement thereof, means 85 pressing said movable part into clamping relation with said fixed part, and means for moving said movable clamping part against the action of said pressing means, out of clamping position.
17. A barber or like chair head rest, comprising a paper roll and a paper clamp, said clamp comprising a fixed part and a movable part, said movable part, when moved to unclamping position, moving up and away 90 from the lower edge of the paper, a spring-pressed part pressing said movable part into clamping relation with said fixed part, and means for moving said movable clamping part out of clamping position, said means 95 comprising a rock-shaft having a finger-piece thereon and an arm adapted to transmit the rocking movement of said shaft to said movable clamping part.
18. A barber or like chair head rest, comprising a paper roll and a paper clamp, said clamp comprising a fixed part, a movable member, said movable member having a loose connection with the headrest, and means for moving said movable member, said means 100 comprising a rock-shaft having means thereon adapted to impart a rocking and sliding movement to said movable member.
19. A barber or like chair headrest, comprising a paper roll and a paper clamp, said 105 clamp comprising a fixed part and a movable member, said movable member comprising a plate having slotted ears permitting a rotating and sliding movement thereof, and means for moving said movable member out 110 of clamping position.
- In witness whereof, I have hereunto signed my name.

GIUSEPPE CARMELO LARAIA.
